UNITED STATES PATENT OFFICE.

EDSON C. ANSON AND HARRY E. KEIM, OF GLENWILLARD, PENNSYLVANIA.

AUTOMOBILE-SIGNAL.

1,303,754.

Specification of Letters Patent. Patented May 13, 1919.

Application filed March 20, 1918. Serial No. 223,600.

To all whom it may concern:

Be it known that we, EDSON C. ANSON and HARRY E. KEIM, citizens of the United States, residing at Glenwillard, in the county 5 of Allegheny and State of Pennsylvania, have invented new and useful Improvements in Automobile-Signals, of which the following is a specification.

This invention relates to an automobile 10 signaling device and has for its primary object to provide a device of this character of simple substantial construction which may be easily operated by the occupant of the machine.

15 An object of the invention is the simple manner of constructing the different parts so that the expense of the device is materially reduced.

Another object of the invention is forming 20 the letters of radium paint upon a signal blade so that the device may be used at night as well as in the day.

With these and other objects in view the invention will be better understood from the 25 following detailed description taken in connection with the accompanying drawings wherein:

Figure 1 is a detailed view of a wind shield showing our invention applied thereto.

30 Fig. 2 is a view showing the blade in operative position and one of the side plates removed.

Fig. 3 is an enlarged top plan view of the device.

35 Fig. 4 is a vertical sectional view thereof.

Fig. 5 is a top plan view of the spacing member.

Again referring to the drawings the numeral 1 designates the casing composed of 40 a spacing member 2 and side plates 3 and 4 secured to the spacing member. The spacing member 2 is of such a shape that the casing has an open front 5 for the purpose hereinafter described. The spacing member 2 is 45 further provided with laterally extending fingers 6 each provided with an arcuate recess 7 so as to engage a portion of the rod 8 of the wind shield and coöperate with a clamp element 9 for securing the device to 50 the wind shield. Passing through the fingers 6 and the element 9 is a thumb bolt 10.

Fastened in the side plates 3 and 4 is a bolt 11 the major portion of the length of which is square in cross section as indicated

55 at 12 while the remaining portion has screw threaded engagement with a pair of binding nuts 13. Engaging the square portion of the bolt is one end portion of a signal blade 14 and the same is suitable spaced from the side plates 3 and 4 by washers 15.

60 Each of the signaling letters 16 on the blade is made of radium paint so that the letters will be illuminated at night. These letters are effectively shielded and protected by the casing when the signal blade is removed to an inoperative position. For throwing the signal blade to operative or inoperative position we provide an arm 17 65 arranged in convenient reach of the operator of the machine. From this construction it 70 will be seen that in a very simple manner we are able to convey to drivers of other machines the intentions of the driver ahead. It is of course to be understood that the nuts 13 75 can be tightened to such an extent that their frictional engagement with the blade 14 will hold the same in an operative or an inoperative position irrespective of the vibration of the machine. When the blade is within the 80 casing it is effectively protected against the weather or the rubbing action of foreign bodies.

85 From the foregoing description taken in connection with the accompanying drawing it should be apparent that we provide a device of simple construction composed of few parts which may be manufactured and assembled at a relatively low cost and by means of which signals may be displayed in the 90 day as well as at night and the signaling element fully protected when in an inoperative position.

Having described our invention what we claim is;

95 An automobile direction signal comprising a casing including a spacing member forming the top, back and bottom walls of the casing, parallel side plates secured upon said spacing member, clamping members extending from said spacing member and engageable upon a wind shield, said casing extending vertically and having its outer edge open, a shaft journaled transversely through the upper portion of said casing and having its portion within the casing angular in cross 100 section, a signal arm secured upon the angular portion of said shaft and normally disposed in a vertical position within said cas- 105

ing in substantially conforming relation thereto, and a normally horizontally disposed handle secured upon the projecting end of said shaft and extending within convenient reach of an operator, depression of said handle resulting in upward swinging movement of said signal arm to protrude

beyond said casing, said swinging arm returning by gravity to its initial position when pressure upon said handle is released. 10

In testimony whereof we affix our signatures.

EDSON C. ANSON.
HARRY E. KEIM.
